CORRUGATION PUNCH PRESS

William F. Rethwisch, National City, and Dale S. Harding,
Chula Vista, Calif., assignors to Rohr Corporation,
Chula Vista, Calif., a corporation of California

Filed Oct. 7, 1963, Ser. No. 314,191
14 Claims. (Cl. 72—397)

This invention relates generally to machines for fabricating honeycomb core and more particularly to a corrugation punch press for forming corrugations in the metallic ribbon used in the fabrication of the honeycomb core.

In a core fabricating machine such as disclosed in Patent No. 3,079,487, issued to F. H. Rohr for Method and Apparatus for Fabricating Honeycomb Core, a corrugated metallic ribbon is folded back and forth upon itself to form the successive layers of the core. In order to form quality high strength core in this manner, it is necessary that the corrugations in the ribbon be precisely formed and coined without introducing appreciable distortion or strain into the ribbon material during the corrugation process. This is imperative in order that the corrugated ribbon will have the same spacing from node to node such that the nodes of the confronting ribbon layers will be aligned and abutted preparatory to the resistance welding of the nodes together to form the cells of the core. As disclosed in the aforesaid patent, wherein provision is made for programming the corrugated ribbon of successive sections of different thickness to provide a core of predetermined structural pattern and density, it is equally important that the corrugation configuration and nodal spacing be precisely maintained since these parameters provide the reference datum in determining points in the fabricated core at which changes in density are to occur in accordance with the predetermined pattern.

Various corrugation methods have heretofore been employed such, for example, as for passing the flat ribbon through a pair of corrugating gears, as disclosed in Patent No. 2,843,722 issued to Milton G. Wegeforth for Apparatus and System for Producing Honeycomb Core. This method, however, has not been found to be entirely satisfactory in the production of high quality metallic core for the reason that the meshing gears tend to form several corrugations at a time therebetween, and the ribbon which must be drawn from the supply to form these corrugations, becomes unduly stretched and strained in the corrugation process. The gears, moreover, do not coin the corrugations, that is they do not form sharp bends and give a permanent set to the ribbon such that it becomes precisely formed and spaced from node to node.

Corrugation punch presses of the type disclosed in the aforesaid patent of Fred H. Rohr provide the required coining of the metallic ribbon as the corrugations are formed, but have not entirely solved the problem of minimizing the stresses and strains due to the drawing and inordinate working of the ribbon as the corrugations are formed, even where, as in the aforesaid case stages of spring loaded corrugation punches are used in the operation.

In accordance with the arrangement of the corrugation punch press of the present invention, upper and lower corrugating dies, respectively have differentially spring loaded die members, cooperate during the initial closing of the dies to yieldably clamp and hold a previously formed, substantially V-shaped ribbon corrugation between the spring loaded members and, thereafter, as the dies continue to close, to brake the unformed ribbon therebetween in two steps, to thus form the two sidewalls of a new corrugation, as the holding die members bottom in successive order, after which the dies, together and as a unit with their holding die members, forcibly move to-

2

gether to coin the newly formed corrugation therebetween. In this operation, the braking action involves essentially a translatory swinging movement of the unformed ribbon portions about certain of the tooth edges of the dies which act as pivotal points. The result of this action is that the necessary drawing of the ribbon from the storage reel is due essentially to the braking action, and such working of the ribbon material as may occur in the corrugation process, is thus held to a minimum, to thus substantially prevent the introduction of stresses and strains into the corrugated ribbon. As will become more fully apparent as the description proceeds, certain nodal portions of the ribbon experience no working of the metal at all, save for the ultimate coining which is desired; the nodal portions merely being translated, as required, in the corrugation process to place the nodes alternately at the peaks and valleys of the corrugated ribbon.

An object of this invention is to provide a new and improved corrugation press for corrugating metallic ribbon which affords all of the advantages of prior corrugators while substantially obviating the difficulties thereof.

Another object is to provide a corrugation press which effectively brakes an unformed ribbon in successive steps to form a new corrugation and finally coins the same as the press closes.

Still another object is to provide a corrugation press which utilizes differentially biased die members to brake successive unformed portions of a ribbon to form a new corrugation therefrom as the die members move to bottom in successive order.

Yet another object resides in the provision of a corrugation die press wherein differentially biased holding die members initially move to clamp a previously formed ribbon corrugation therebetween, wherein the holding member having the greater bias serves as an anvil to brake a first portion of the unformed ribbon thereon as the lesser biased member moves to bottom on its die and wherein the greater biased member moves to bottom on its die as a second portion of the unformed ribbon brakes between the dies.

An additional object is to provide a corrugation press in which the drawing of the ribbon required to form a new ribbon corrugation is due essentially to the braking of successive portions of the unformed ribbon.

Still other objects, features and advantages of the present invention are those inherent in or to be implied from the novel construction combination, and arrangement of parts of the preferred embodiment of the invention, hereinafter to be described, which has been constructed in accordance with the best mode thus far devised for practicing the principles of the invention. In the accompanying drawings which disclose this preferred embodiment:

FIG. 1 is a view in elevation of the corrugation press of the present invention;

FIG. 2 is a view from the under side of the upper die of the corrugation press as viewed along line 2—2 of FIG. 1 and rotated 90° counterclockwise from the position of FIG. 1;

FIG. 3 is an enlarged view of the upper die of FIG. 2;

FIG. 4 is a sectional view taken along the line 4—4 of FIG. 3;

FIG. 5 is a view in elevation of the opposing spring loaded holding die members;

FIG. 6 is a sectional view of the opposing upper and lower dies;

FIGS. 7 to 9 are schematic sectional views showing the successive steps of forming a ribbon corrugation between the dies of FIG. 6;

FIGS. 10a to c are diagrammatic views illustrating further details of the corrugation forming process; and

FIG. 11 shows a fluted ribbon corrugation.

Referring now to the drawings for a more complete understanding of the invention, and first more particularly to FIGS. 1 and 2 thereof, 10 and 11 designate fixed and movable die supports which, in practice, may be referred to as shoes, but for purposes herein, conveniently may be considered as the anvil 10 and the ram or punch 11 of a conventional punch press. Support 11 is normally positioned above fixed support 10 and is slidably mounted on the upstanding and suitably spaced cylindrical guides 13 and 14 for movement forcibly toward and away from the fixed support. For this purpose, guides 13 and 14 are suitably secured to fixed support 10, and movable support 11 is suitably driven from a power source acting through its coupling member 12. Hubs 15 and 16 on support 11 extend the bearing surface afforded thereby on guides 13 and 14. Hubs 15 and 16 and guides 13 and 14 are disposed concentrically with respect to semi-cylindrical lateral extensions 17 and 18 of support 11.

A die set comprising dies generally designated 19 and 20, respectively, are suitably secured to the fixed and movable supports 10 and 11, as by screws 21, FIG. 2, which preferably are seated in countersunk openings 22. Dies 19 and 20 are generally similar, and the same reference characters therefore, will be applied to the same or like elements of these dies throughout the several views.

Each of dies 19 and 20 comprises a forming die member 23 having one tooth 24, and a relatively movable holding die member 25 having two teeth 26. Die members 23 and 25 for both dies 19 and 20 are identical and their opposing teeth 24 and 26 complement each other such that the same intermesh as depicted in FIGS. 1 and 7 to 9. The line of engagement between the teeth also depicts the corrugation configuration to be imparted to a metallic ribbon 27 interposed therebetween, as depicted in FIGS. 6 to 9. As may be seen from this configuration, the resulting corrugations in the ribbon will be generally V-shaped with flattened surfaces or welding nodes 28 and 29 respectively provided at the crests and valleys of corrugated ribbon.

Referring now more particularly to FIGS. 1 to 4, it will be seen that each forming die member 23 is secured at the ends thereof, as by countersunk screws 30, to a pair of end plates 31 which, in turn, are secured by countersunk screws 32 to the die guide block and mounting member 33. Member 33 has a mounting flange 34 which carries the aforementioned screws 21 for mounting dies 19 and 20 on their respective supports 10 and 11. End plates 31 also carry screws 21 which serve further for this purpose.

Die members 23, 31 and 33 when assembled and secured together, as aforedescribed, provide a guide channel 35, FIG. 4, for the holding die member 25 which is provided with a flange or shoulder 36. Guide channel 35 is appropriately widened at 37 to accommodate the shoulder and also provide a seat therefor to limit the movement of holding die member 25 forwardly or outwardly with respect to the forming or corrugating die member 23, as depicted in FIG. 4. It will be noted that the widened channel 37 has a greater length than that of the shoulder thereby to permit limited relative movement between the die members 23 and 25. Thus, when each die 19, 20 is mounted in position on its respective support 10, 11, die member 25 for each die is limited in its movement in the opposite direction as the shoulder engages the mounting surface of its associated support, as may best be seen in FIGS. 1 and 9 wherein the dies 19 and 20 are shown to be closed and the die members 25, in such case, are properly shown to be bottomed on their respective supports. When die members 25 are thus bottomed, they effectively become a unit with their respective corrugator die members 23, and teeth 26 of each member 25 effectively act as a unitary tooth structure with their associated tooth 24. This is important in the precision forming of corrugations in metallic materials such as stainless steels wherein it is desired to coin the formed

corrugations in the final blow imparted thereto by the punch press in the instant of closing of the dies on the ribbon interposed therebetween.

Holding die members 25, as may best be seen in FIGS. 5 and 6, are spring loaded, as by coil springs 38, so as to be normally extended yieldably outwardly or forwardly of their respective forming die members 23, these members being sufficiently elongated, as required, to corrugate ribbons of various widths. A plurality of springs are employed for each die member, and a socket 39 is provided therein for seating each spring 38. Similarly, supports 10 and 11, are provided with sockets 40 which also serve to seat the springs, sockets 40 being aligned with and complementing the sockets 39 of the die members 25.

For reasons which will become more fully apparent as the description proceeds, die members 25 are differentially spring loaded, the spring loading of die member 25 of die 19 being made greater than that of member 25 of die 20, as depicted in FIG. 5, by using two more springs 38 for die 19.

It will be understood that whereas differential spring loading has been particularly disclosed herein, the differential bias and yieldable urging of the holding die members 25 may be accomplished by other means such, for example, as by using air pressure.

With the parts positioned as disclosed in FIG. 6, the punch press is about to begin a new cycle of operations to form a new corrugation in ribbon 27, the ribbon having been just previously advanced one corrugation by sliding 30 over the teeth 26 of the lower holding die member 25. The ribbon preferably is advanced relative to the dies, as aforedescribed, by a hitch feed mechanism such as disclosed and claimed in the copending application of Elbert M. Lacey, Jr., for Method and Apparatus for Feeding 35 Metal Strips, now Patent 3,123,125, Ser. No. 78,720, filed December 27, 1960.

With ribbon 27 thus seated on the lower die member 25, the opposing member 25 first engages the ribbon during the initial closing of die 20 toward die 19, the ribbon then being clamped yieldably between the upper and lower ribbon holding members 25, as depicted in FIG. 7, at which time the forming of the first portion of a new corrugation is about to begin. As die 20 continues to move toward die 19, the same moves relative to its holding die member 25 which cannot move at this time because of the greater spring force acting on the lower holder member 25 which does not move until after the upper die member 25 has bottomed on support 11.

During this relative movement of die member 23 with respect to its holding die member 25, a first unformed portion 41, FIG. 7, of ribbon 27, corresponding to one side of a new corrugation, is formed between tooth 24 of die 20 and the confronting tooth 26 of die 19 as the dies take the position as shown in FIG. 8.

Members 23 and 25 of die 20 now move as a unit to thus move holding member 25 of die 19 yieldably against its opposing spring force until the same bottoms on support 10, as disclosed in FIG. 9. During this movement, a second unformed portion 42, FIG. 8, of ribbon 27, corresponding to the remaining sidewall of the new corrugation, is formed between the confronting teeth 24 of the opposing corrugating die members 23. In the position of FIG. 9, both die members 25 being bottomed, the newly formed corrugation is coined in the instant of forcible closing of die 20 on die 19.

Referring now more particularly to FIGS. 10a to c, for a more detailed discussion of the metal working aspects involved in the forming of the new corrugation from ribbon 27, as aforedescribed, it will be seen that the unformed ribbon portion 41, which has a length A corresponding to the sidewall of the corrugations to be formed, bears critically at P1 on tooth 26 of holding die member 25 of die 19, and also bears critically at P2 on tooth 24 of forming die member 23 of die 20. As the dies close 70 and the forming occurs, ribbon portion 41 brakes about

the point P1 in response to pressure applied at the point P2. It will be appreciated that the ribbon slides for a small distance over the point P2 of tooth 24 until the same reaches the position of FIG. 10b. In the braking action of the unformed ribbon portion 41, the end of the same follows the circular path about point P1 indicated by the dashed line 43. That diminishing portion of the unformed ribbon lying between this dashed line and point P2, of course, experiences a combined sliding and braking movement over point P2. While a purely braking action would be ideal, no adverse effects are manifested.

A second unformed ribbon portion 42, also having a length A, brakes about the point P3 on tooth 24 of die member 23 of die 20, as die member 25 of die 19 moves to bottom on support 10, and a combined sliding and braking action of the ribbon occurs about the point P4. The braking action of unformed ribbon portion 42 about point P3 thus is such that the end of the ribbon portion follows the circular path indicated by the dashed line 44 shown in FIG. 10b.

That portion of the unformed ribbon, which lies between points P2 and P3, is designated 45 and has the nodal length B. Ribbon portion 45 is simply translated to the base of tooth 24 of die member 23 of die 19 as member 25 thereof moves to bottom on the die support 10. As a practical matter, unformed but coined ribbon portion 45, together with ribbon portion 41, may be considered to be a first unformed ribbon portion, in the same sense that the corresponding unformed but coined ribbon portion 46, FIG. 10c, which lies between the points P4 and P5 at the closing of the dies, together with ribbon portion 42, may be considered to be a remaining ribbon portion, required to form a new complete corrugation, which will thus be made up of ribbon portions 41, 45, 42 and 46, as may best, be seen in FIG. 10c.

Although the corrugation width, i.e., as measured from node to node, may be seen to be B plus D, a length of ribbon corresponding to 2B plus 2A is required to form a new corrugation. Of this length, as has been described, there is no working of the B portions; only coining. D minus B, of course, does not equal 2A, since purely braking does not occur in the forming of the A portions; but this is substantially the case, and the ultimate coining of the formed ribbon in the region of points P2 and P4 removes any adverse effects which may have been introduced in the previous working of the material as it slides over the teeth at these points. In effect, the substantial length of each A portion is simply translated in a swinging movement of the unformed ribbon portion about the edge of one of the die teeth.

The results of a corrugation process as aforescribed are, first, precision forming of the ribbon corrugations and, second, high quality blocks of honeycomb core when the same are fabricated from the precision corrugated ribbon. Such blocks are undistorted and unwarped and have optimum welds at abutting nodes which are aligned consistently from node to node. The fabrication of cores from such ribbon desirably may be programmed with assurance that the corrugations will be uniform in spacing and the nodes will properly align and abut preparatory to welding of the same together.

The manner of operation of the differently biased corrugation press of the present invention also lends itself to the precision forming of perforated ribbon, as more fully described in the copending application of Elbert M. Lacey, Jr., et al., for Method and Apparatus for Perforating and Corrugating Metallic Ribbon, Ser. No. 329,744, filed Dec. 11, 1963, now Patent Number 3,307,384. It suffices herein merely to state that protuberances formed in the ribbon upon perforation of the same are generally pressed and formed by the corrugation press into an eyelet construction which prevents incipient tearing and fracturing of the ribbon in the region of the perforations.

The differentially biased corrugation press of the present invention also lends itself to the forming and coining of

corrugations having fluted sidewalls 47, as depicted in FIG. 11. In such case, the sidewalls of teeth 24 and 26 are correspondingly fluted.

It will be apparent from the foregoing that a corrugation press has been provided which is well adapted to fulfill the aforesigned object of the invention. It will be apparent, moreover, that this invention may be embodied in other forms or carried out in other ways without departing from the spirit or essential characteristics thereof. The present embodiment of the invention is therefore to be considered as in all respects illustrative and not restrictive, the scope of the invention being indicated by the appended claims, and all changes which come within the meaning and range of equivalency of the claims are intended to be embraced therein.

Having thus described our invention, what we claim as new and useful and desire to secure by Letters Patent is:

1. In a punch press for precision forming of corrugations successively one at a time in metallic ribbon, the combination of opposing die means respectively comprising yieldably extended die portions for braking and forming a first unformed portion of the ribbon therebetween thereby to form only a first portion of a corrugation in the ribbon as one of the die portions moves yieldably to bottom on its die means and for braking and forming a second unformed portion of the ribbon thereby to form only the remaining portion of said corrugation as the other die portion moves yieldably to bottom on its die means.
2. In a punch press as in claim 1, said die means and the die portions bottomed thereon being constructed and arranged for unitary closing together thereby to coin said formed corrugation therebetween in the instant of closing of the die means.
3. In a punch press for precision forming of corrugations successively one at a time in metallic ribbon, the combination of opposing die means having matching surfaces corresponding to the corrugation configuration of a ribbon to be corrugated therebetween and respectively comprising differentially biased die portions for engaging and clamping a previously formed corrugation of the ribbon, for braking a first unformed portion of the ribbon thereby to form only a first portion of a new corrugation in the ribbon as one of the die portions moves yieldably to bottom on its die means, and for braking a second unformed portion of the ribbon thereby to form only the remaining portion of said new corrugation as the other die portion moves yieldably to bottom on its die means.
4. In a punch press as in claim 3, said opposing die means comprising die teeth having said matching surfaces, and said die teeth being intermeshed in the instant of closing of the die means thereby to coin the new corrugation therebetween.

5. In a punch press for precision forming of successive substantially V-shaped corrugations in metallic ribbon, the combination of opposing relatively movable die means having matching surfaces corresponding to the corrugation configuration of a ribbon to be corrugated therebetween as the die means are closed, said die means respectively having yieldably biased and linearly movable die portions which extend into confronting relation to the ribbon to clamp a previously formed corrugation therebetween, one of said die portions being yieldably biased to a lesser extent than the other, said die means being operable to brake a first unformed portion of the ribbon therebetween thereby to form a first one-half portion of a new V-shaped corrugation in the ribbon as the lesser biased die portion moves yieldably to bottom on its die means, said die means being operable to brake a second unformed portion of the ribbon therebetween thereby to form the remaining one-half portion of said new corrugation as the other die portion moves yieldably to bottom on its die means, and said die means being operable as the same move relatively to closed position to coin said new corrugation to said configuration.

6. In a punch press for precision forming of corrugations in metallic ribbon, the combination of normally separated dies relatively movable toward each other to closed position, said dies having opposing teeth corresponding in configuration to the corrugations to be formed in the ribbon and movable into meshing relation as the dies move into said closed position, said dies each having only one fixed tooth disposed for meshing engagement with the fixed tooth of the other for forming said corrugations one at a time upon successive closing movements of the dies to closed position, and said dies respectively comprising differentially spring loaded toothed die portions which move yieldably into said meshed relation during the initial relative movement of the dies toward each other and yieldably move in successive order to bottom on their respective dies during continued relative movement of the dies to said closed position.

7. In a punch press as in claim 6, certain of the opposing teeth of said dies serving to engage and clamp at least one previously formed corrugation of the ribbon therebetween and certain other of said opposing teeth serving to engage first and second unformed portions of the ribbon to form first and second portions of a new corrugation therebetween as the die portions bottom respectively in said successive order.

8. In a punch press as in claim 6, one of said dies being fixed in a lower position with its spring loaded die portion normally extended upwardly of the same, the other of said dies being movably mounted for lowering movement toward said fixed die and normally having its spring loaded die portion depended and extended therefrom into confronting relation to said upwardly extending die portion.

9. In a punch press as in claim 8, said upwardly extending die portion having greater spring loading than said depending die portion whereby the same retains its upwardly extended position until said depending die portion has bottomed on its die.

10. In a punch press as in claim 9, said die portions being engageable with a corrugated portion of a ribbon being corrugated to clamp the same therebetween, said fixed tooth of said movable die and a matching tooth on said upwardly extending die portion having cooperating surfaces for braking and forming therebetween a first unformed portion of the ribbon to form a first portion of a new corrugation therefrom as said depending die portion moves yieldably to bottom on its die.

11. In a punch press as in claim 10, said upwardly extending die portion being driven by said movable die and its bottomed die portion to bottom in said fixed die, said fixed teeth of said movable and fixed dies having cooperating surfaces for braking and forming therebetween a second unformed portion of the ribbon to form the remaining portion of said new corrugation therefrom as said upwardly extending die portion moves yieldably to bottom in the fixed die.

12. In a punch press for precision forming or corrugations in metallic ribbon, the combination of a fixed support, a movable support mounted above the fixed support for guided movement toward and away from said fixed support, first and second dies respectively secured to said fixed and movable supports and having opposing teeth corresponding in configuration to the corrugations of a ribbon to be corrugated therebetween as the dies are closed, said first and second dies each having only one fixed tooth disposed for meshing engagement with the fixed tooth of the other for forming said corrugations one at a time upon successive closing movements of the dies to closed position, and said first and second dies respectively comprising first and second toothed movable die portions mounted for limited movement on their respective dies, said first and second die portions each having a plurality of sockets disposed in spaced relation along the length thereof, said fixed and movable supports having a plurality of sockets respectively complementing and aligned with those of said die portions individual thereto, a plurality of springs disposed in certain of the complementary sockets of the fixed support and said first die portion for yieldably urging the first die portion to normally extend outwardly from said first die and toward said second die, and a lesser number of springs disposed in certain of the complementary sockets of the movable support and said second die portion for yieldably urging the second die portion to normally extend outwardly from said second die and toward said first die.

13. In a punch press as in claim 12, said first and second dies each having a guide channel for its die portion, each said channel comprising a main opening which extends from the toothed surface of the die and a widened portion in the region of attachment of the die to its support, each of said die portions having a shoulder disposed in the widened portion of said channel opening in its die, and each said shoulder having a length less than the length of said widened portion of the channel opening thereby to provide said limited movement of said die portions on their respective dies.

14. In a punch press as in claim 12, said opposing teeth being substantially V-shaped and each tooth being flattened at its tip and at its base and having each side wall thereof fluted.
